UNITED STATES PATENT OFFICE.

WILLIAM F. REINLIE, OF CHICAGO, ILLINOIS, ASSIGNOR TO ILLINOIS TOOL WORKS, OF CHICAGO, ILLINOIS, A CORPORATION OF ILLINOIS.

CHUCK.

1,254,071.

Specification of Letters Patent. Patented Jan. 22, 1918.

Application filed January 15, 1917. Serial No. 142,343.

To all whom it may concern:

Be it known that I, WILLIAM F. REINLIE, a citizen of the United States, residing at Chicago, in the county of Cook and State of Illinois, have invented a certain new and useful Improvement in Chucks, of which the following is a specification.

My invention relates to chucks for holding abrasive grinding sticks, and the object 10 of the invention is to provide means whereby the grinding stick will be held in the chuck very securely and yet will not be in danger of being crushed under the holding pressure. It will be understood that in tool finishing 15 and for other purposes in the mechanic arts, rapidly rotating grinding sticks or "points" are employed. These sticks or points are subject to breakage if subjected to too great a stress and yet they must be firmly held, for 20 they commonly rotate at a very high speed and are frequently forced with considerable pressure against hard metallic surfaces. My purpose is, therefore, to provide a chuck in which the grinding stick can be firmly 25 bedded and held. Contributory to this general purpose, it is my object to provide a chuck of this character which shall be simple and efficient in construction and easy to manipulate.

30 I obtain my object by the mechanism illustrated in the accompanying drawings, in which:

Figure 1 is an axial section of a chuck embodying my invention. It shows the grinding 35 stick in position.

Fig. 2 is an end view of the left end of Fig. 1.

Fig. 3 is an end view of the right end of Fig. 1.

40 Similar numerals refer to similar parts throughout the several views.

Referring to the drawings, the shank 1 is of any form suitable for fastening it into the rotating spindle of the grinding machine.

45 At its head end it has a threaded portion 2 onto which screws a cap 3. At the forward end this cap is conically tapered internally, and preferably also externally. Within the tapered portion of the cap is a ring 4 of

50 lead or similar material capable of having its configuration changed when subjected to pressure. For convenience I will refer to it as "plastic" although it is less plastic than many substances characterized by that term.

55 The ring surrounds the body of the grinding

stick 5 and extends to a point flush with the end of the cap. The diameter at the mouth of the cap is appreciably greater than the diameter of the grinding stick so as to accommodate the lead ring in between. The 60 purpose is to support the stick at a point as far forward as possible, not beyond the cap itself. It will be understood that these grinding sticks or points when used, for example, in grinding hobs, are subjected to great stress 65 and revolve at very high speed and need all the support that can be given them, especially at the front end. In order to give an especially firm backing at the inner end, the shank 1 occupies practically the entire cross 70 sectional area of the cap 3 and backs up the grinding stick. Hence there is no possibility for the stick to back away from the work or in any way loosen the grip of the parts. In the form shown the cap is provided with 75 sockets 6 for receiving the points of a spanner wrench or other suitable tool by which the cap may be rotated.

In operation, the parts are first loosely assembled in the relative positions shown in 80 Fig. 1. The ring 4 is originally but slightly larger in internal diameter than the external diameter of the grinding stick and it also approximately fits the internal conical surface of the cap. But as soon as reasonable pressure is exerted to screw the cap onto the shank 1, the cap begins to compress the plastic ring onto the grinding stick, the longitudinal motion of the plastic ring being limited by the head end of the shank. Consequently, a comparatively small amount of 85 turning of the cap after the parts are assembled as tight as they can be by the fingers is sufficient to grip the body of the grinding stick firmly and thereby secure it so that it 90 will rotate with the chuck. On account of the plastic characteristic of the material of which the compression ring 4 is formed, the pressure upon the various points of the grinding stick is equalized and hence, not 95 only is the grinding stick held very firmly, but the danger of breaking it by pressure from the chuck is eliminated. The device is of simple form and few parts and may be readily taken apart by simply unscrewing the 100 cap from the shank.

Having thus described my invention, what I claim as new and desire to secure by Letters Patent, is:

1. A chuck for holding short grinding 110

sticks, said chuck having an internally tapered cap surrounding the stick, a plastic ring surrounding the stick and located between the stick and the cap, and a shank entering the back of the cap and forming a backing for both the ring and the stick.

2. A chuck for holding short cylindrical grinding sticks having squared inner ends, said chuck having an internally tapered cap surrounding the stick and annularly spaced therefrom at the mouth, a plastic ring between the stick and the cap, the outer end of the ring being substantially flush with the outer end of the cap and the inner end of the

stick being substantially flush with the inner end of the ring, and a shank screwing into the back end of the cap and forming a backing for both the stick and the ring.

3. A chuck for holding short grinding sticks, said chuck having an internally tapered cap surrounding the stick, a ring surrounding the stick and located between the stick and cap, and a shank entering the back of the cap and abutting corresponding ends of the ring and stick.

In witness whereof, I have hereunto subscribed my name.

WILLIAM F. REINLIE.
